UNITED STATES PATENT OFFICE.

AGNES E. DOYLE, OF ST. MARIES, IDAHO.

REFRIGERATOR.

Application filed December 17, 1924. Serial No. 756,612.

This invention relates to a refrigerator, the general object of the invention being to provide means whereby the interior of the refrigerator is kept cool by the evaporation 5 of water placed in porous bags arranged about the refrigerator.

This invention also consists in certain other features of construction and in the combination and arrangement of the several 10 parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a front view of the device.
20 Figure 2 is a vertical sectional view therethrough.

Figure 3 is a transverse sectional view showing the door of the refrigerator open and the top raised.

25 Figure 4 is a perspective view of one of the water bags.

Figure 5 is an enlarged sectional view on line 5—5 of Figure 4.

Figure 6 is a detail view.
30 In these views, 1 indicates a casing preferably formed of metal and which has its front 2 removably and hingedly connected at its lower edge with the bottom of the case, as shown at 3. Slotted braces 4 are provided 35 for fastening the ends of the movable front to the inner side walls of the case. Removable shelves 5 may be placed in the case, said shelves being formed of spaced metal bars.

Bags or containers 6, formed of canvas or 40 other porous material, are held against the sides and top of the case by sheets 7 of wire mesh so that when these bags are filled with water the evaporation of water seeping through the walls of the bags will act to cool 45 the interior of the case in the well known manner. A wooden base 7 is provided for the device and a perforated pan 8 is placed in a recess 9 formed in the base, under the case, this pan catching some of the water 50 escaping from the bags and this water will

pass through the perforations and soak the wooden base and thus increase the cooling effect due to the evaporation. One of the bags is secured to the door or front 2 and the top bag 6' is carried by a plate 10 which is 55 adapted to rest upon the top of the case and may be held thereon by the pins 11 engaging the holes 12. By removing this upper bag 6' the side bags can be removed from their spaces formed by the walls of the case and 60 the wire mesh without difficulty. The top of each bag is formed by a flap 13 which is a continuation of one of the side walls of the bag and the flap is held in closed position by the metal clip 14 engaging the abutting 65 edges of the flap and one of the side walls of the bag. Each bag is provided with a ring 15 at its upper end so that the bag can be suspended from hooks such as 16, or other suspension means. Latch means 17 are provided for holding the door 2 in closed position and handles 18 may be arranged on the base to facilitate handling of the device.

From the foregoing it will be seen that I have provided a simple and inexpensive 70 refrigerator, the contents of which are kept cool by the evaporation of water contained in the canvas bags which surround the case.

It is thought from the foregoing description that the advantages and novel features 80 of my invention will be readily apparent.

I desire it to be understood that I may make changes in the construction and in the combination and arrangement of the several parts, provided that such changes fall within 85 the scope of the appended claims.

What I claim is:—

1. A refrigerator including a metal case, a wooden base therefor having its upper face recessed, a perforated pan arranged within 90 said recessed base, a movable front for the case hinged to the bottom thereof, absorbing elements arranged at the sides, ends and top of said case with the side and end elements extending into the perforated pan as and for 95 the purpose specified.

2. A refrigerator including a metal body, a wooden base having its upper face recessed, a shallow perforated pan arranged within the recessed base, the top of said body 100

having a plurality of holes therein, a removable plate, downwardly depending pins on said plate adapted to engage the holes within the top of the body, a movable front for the body hinged to the bottom of said body, absorbing elements arranged at the sides, ends and the top of the body with the sides and

end elements depending into the perforated pan and sheets of wire-mesh arranged over the absorbing elements to retain them in position relative to the body of the refrigerator.

In testimony whereof I affix my signature.

AGNES E. DOYLE.
